United States Patent Office

Des. 203,069
Patented Nov. 30, 1965

203,069

THERMOMETER UNIT

Eric Albury Mitchell and Yvonne Jacqueline Mitchell,
both of 40 Dougharty Road, West Heidelberg, Victoria,
Australia

Filed Sept. 8, 1964, Ser. No. 81,628

Claims priority, application Australia Mar. 16, 1964

Term of patent 14 years

(Cl. D52—7)

Fig. 1

Fig. 2

Fig. 4

Fig. 3

Fig. 5

FIGURE 1 is a side elevation of a thermometer unit, showing our new design;

FIGURE 2 is a top plan of the thermometer unit shown in FIGURE 1;

FIGURE 3 is an end elevation thereof viewed from the left of FIG. 1;

FIGURE 4 is a bottom plan view thereof; and

FIGURE 5 is an end elevation thereof viewed from the right of FIG. 1.

The undisclosed side of the thermometer unit is a mirror image of the side shown.

We claim:

The ornamental design for a thermometer unit, substantially as shown and described.
